US00D693189S

(12) **United States Design Patent**
Facey

(10) **Patent No.:** **US D693,189 S**
(45) **Date of Patent:** **** Nov. 12, 2013**

(54) **CAKE POP MOLD**

(76) Inventor: **Jeanette Facey**, Osterville, MA (US)

(**) Term: **14 Years**

(21) Appl. No.: **29/422,415**

(22) Filed: **May 21, 2012**

(51) **LOC (9) Cl. 07-04**

(52) **U.S. Cl.**

USPC **D7/674; D7/354**

(58) **Field of Classification Search**

USPC D7/672-677, 300, 354-364, 368, 369.4, D7/402, 410, 505, 506, 554.3-554.4, 601, D7/611, 654, 669, 680, 681, 683, 684, 685, D7/686, 687, 693, 608, 605, 602, 624.2, D7/619.1-625, 510, 523, 527, 528, 540, D7/542, 545, 546, 302, 304, 306; D9/341, D9/424-432, 449, 456, 737, 757, 758, D9/762; 249/91, 92, 105, 168, 117, 118, 249/119, 121, 123, 124, 130, 132, 135, 126, 249/170; 426/134, 421, 515, 67, 68, 91, 95, 426/96; 206/521.1-521.8; 220/675, 220/737-739, 902, 903, 673; D1/101, 102, D1/105, 103, 705; 62/457.1-457.9; D24/224; 248/311.2, 154

(57) **CLAIM**

The ornamental design for a cake pop mold, substantially as shown and described.

DESCRIPTION

FIG. 1 is a perspective view of the cake pop mold in a closed position;

FIG. 2 is a front view of the cake pop mold in the closed position;

FIG. 3 is a back view of the cake pop mold in the closed position;

FIG. 4 is a right side view of the cake pop mold in the closed position;

FIG. 5 is a left side view of the cake pop mold in the closed position;

FIG. 6 is a top view of the cake pop mold in the closed position;

FIG. 7 is a bottom view of the cake pop mold in the closed position; and,

FIG. 8 is a perspective view of the cake pop mold in a partially open position.

1 Claim, 3 Drawing Sheets
